G. H. FAICHNEY

THERMOMETER CASE

Filed March 17, 1926

Inventör.

George H. Faichney.

By Harry De Wallace.

Attorney

UNITED STATES PATENT OFFICE.

GEORGE H. FAICHNEY, OF WATERTOWN, NEW YORK, ASSIGNOR TO FAICHNEY INSTRUMENT CORPORATION, OF WATERTOWN, NEW YORK, A CORPORATION OF NEW YORK.

THERMOMETER CASE.

Application filed March 17, 1926. Serial No. 95,343.

This invention relates to improvements in thermometer cases, particularly of the type wherein two thermometers are separately housed in a single tubular body, in which is telescopically disposed a bushing or sheath formed with similar pockets arranged side by side, in which the thermometers are disposed.

The primary object of this invention is to provide novel, simple and effective means for retaining the thermometers in their respective sheaths or pockets, the said means consisting of a non-metallic member of cushion elastic substance, such for example, as sponge rubber, the said member being inserted between and extending into and partially obstructing the said pockets and adapted to be engaged by the thermometers when they are sheathed; the rubber being tenacious, tends to hold the thermometers against accidental shifting in or escaping from their sheaths, and being sufficiently compressible to permit the thermometers to be readily applied to and removed from the case. And a further object is to provide a retainer for thermometers that is gritless and not liable to abrade, chafe, or otherwise disfigure or injure the vitreous bodies of the thermometers.

The various features and parts of the invention will be understood from the detailed description which follows, and by reference to the accompanying drawing, in which—

Figure 1 is an elevational view of the complete case with the cap attached. Fig. 2 is a central longitudinal section showing two thermometers sheathed in the unitary bushing; also showing the disposition of the retaining member. Fig. 3 is an enlarged longitudinal section, taken on line 3—3 of Fig. 2; showing the thermometers held in place by the common retainer. Fig. 4 is a longitudinal section through one of the sheaths, and also through the rubber member, taken substantially on line 4—4 of Fig. 6. Fig. 5 is respectively a top and a bottom end view of the case, as shown in Fig. 1. Fig. 6 is a cross-section taken on line 6—6 of Fig. 3. Fig. 7 is a similar section, taken on line 7—7 of Fig. 4. Fig. 8 is respectively a side and an end elevation of a modification, comprising two oppositely facing retaining members. Fig. 9 is a cross-sectional view similar

to Fig. 6; showing the application of two retainers to the twin sheaths. And Fig. 10 is a view, showing a modified retainer.

In the drawing, 2 represents the tubular body of the case, having a closed end 2' and a normally open externally threaded end 2". 3 represents a cap whose open end 3', is internally threaded for engaging the threads of the body 2. The body 2 is preferably of such diameter as to readily accommodate two thermometers, as 4—4', the latter being disposed in a one-part bushing, which is formed with similar parallel pockets or sheaths 5'—5", the said bushing being preferably made of relatively thin flexible metal, and so constructed and applied that the bushing 5 is held in the tube 2 by its own tension. The bushing 5 is preferably made from a tube which is operated upon by dies or other tools, for creasing or fluting its opposite sides, as at 5", for providing the individual sheaths 5'—5". The creases or tucks 5", are correspondingly slotted, as at 5', to receive a tongue-like portion 6', of a rubber or other tenacious block or member 6, as shown in Figs. 3, 4, 7 and 9. The member 6 is preferably formed with an integral elongated head 6", whose opposite sides 6" are molded to conform to the oppositely curved or rolled walls of the adjacent sheaths, as best seen in Figs. 6, 7 and 9. The head 6" may be of any suitable size and shape and is preferably of such depth as to span the space between the bushing and the adjacent inner wall of the tube 2, as shown in Fig. 6, in order to hold the member 6 from accidental release or displacement, and insure the proper positioning of the tongue 6'. By this construction and arrangement, the tongue 6' affords extremely simple yet effective elastic and tenacious means, for preventing either of the thermometers from shifting within the sheaths 5'—5", or escaping from the body 2, in case the said body is inverted when the cap 3 is removed.

The modified retainer shown in Fig. 10, 100 comprises a single piece or body of rubber 8, having the appearance of a dumb-bell, in which the enlarged ends 8' are substantially cone-shaped and are connected by a relatively thin flat web 8", which performs the same function as the tongue 6' of the retainer 6. According to Fig. 10, the fluted sides of the bushing 5" are formed with reg-

istering circular openings 5^e, which are preferably smaller in diameter than the heads 8'. To apply the member 8, the heads 8' are compressed sufficiently to permit them to be 5 forcibly inserted through the openings 5^e.

The heads 8' are then allowed to expand to their normal size, for rendering the member 8 self-retaining.

Obviously, the tenacious tongue-like portions 6' and 8^a, which comprise the essentially novel and material features of the present invention, may be held in the operative positions by any suitable means, instead of the heads 6' and 8^a, without departing from the spirit of the invention.

Having thus described my invention, what I claim, is—

1. In a thermometer case, the combination with a tubular body adapted to house 20 two thermometers, and a two-pocket sheath telescoping said body, of means for retaining the thermometers in said pockets, comprising a member of the consistency of sponge rubber adapted to be inserted between said 25 pockets and to tenaciously engage both thermometers, said member being supported by an integral enlargement that engages the walls of said sheath.

2. The combination with the tubular body 30 of a thermometer case, and a two-pocket sheath for thermometers telescoping said body, said sheath having a slot connecting with both pockets, of an elastic tenacious member having a tongue adapted to be in-

serted in said slot and partially obstructing 35 both of said pockets, and said member having an enlarged head that engages the outer surface of said sheath and contacts with the inner wall of said tubular body.

3. In a thermometer case, the combination 40 with the tubular body, and a sheath having separate pockets for housing two thermometers telescoping said body, said sheath having an opening formed between said pockets, of an elastic retaining member having a 45 tongue-like portion that is adapted to be inserted in said opening and partially obstructing both of said pockets and having an enlargement extending beyond the tongue-like portion adapted to prevent the accidental release of said tongue-like member.

4. In a thermometer case the combination with a tubular body, and a thermometer sheath having separate parallel pockets telescoping said body adapted to receive two 55 thermometers, said sheath having a slot between said pockets, of means for retaining the thermometers in said sheath comprising a body of tenacious material filling the said slot and extending into said pockets adapted 60 to be frictionally engaged by the thermometers, said retaining body having a head that spans the space between the sheath and the inner wall of said tubular body for holding the retaining body in place.

In testimony whereof I affix my signature.

GEORGE H. FAICHNEY.
